GEORGE F. LE BUS, OF ELECTRA, TEXAS.

SAND-TESTER PUMP.

Application filed August 8, 1927. Serial No. 211,537.

This invention relates to a sand tester pump.

An object of the present invention is the provision of an economical and positive working pump with which a suction can be created on the sand while at the same time cutting off the mud and water from above and allowing the pumping operation to maintain the suction only on the sand and thereby eliminating the expensive method of setting pipes and bailing.

Another object of the invention is the provision of a sand tester pump in which a suction is created on the sand so that mud and water will be removed therefrom which is usually forced back into the sand by high pressure rotary pumps used in the process of rotary drilling.

A further object of the invention is the provision of a sand tester pump which may be raised or lowered by the drill pipe for forcing fluid from the sand through said drill pipe, all initial setting operations of the pump being accomplished by turning the drill pipe to the right thereby eliminating any danger of unscrewing the pipe when controlling valves are being operated for making the test.

A still further object of the invention is the provision of a sand tester pump which may be run into the well and which includes means for thoroughly washing the formation to be tested while at the same time preventing any outlaw fluids from entering the pump or drill pipe.

Another object of the invention is the provision of a sand tester pump which will give an active test from a formation even when the well is caving in, at such a time the circulating pumps being run at the same time the pump is being lowered into the well whereby all cavings are washed out making it possible to reach the sand to be tested.

Another object of the invention is the provision of a releasing packer to cut off all outlaw fluids from above while the formation is being tested and which packer insures the operator that the tester pump can be easily pulled from the well after the test has been made.

This invention will be best understood from a consideration of the following detailed description, in view of the accompanying drawings forming a part of the specification; nevertheless it is to be understood that the invention is not confined to

the disclosure, being susceptible of such changes and modifications which shall define no material departure from the salient features of the invention as expressed in the appended claims.

In the drawings:

Figures 1, 1^a, 1^b, and 1^c show sections of a complete pump with the control valves being held unseated.

Figure 2 is a vertical section of a portion of the pump showing the control valves in position when the pump is being removed.

Figure 3 is a fragmentary vertical section of the pump showing the variable operation or position of the control valves.

Figure 4 is a horizontal section along the line 4—4 of Fig. 1^a.

Figure 5 is a horizontal section taken along the line 5—5 of Fig. 1^b.

Figure 6 is a horizontal section taken along the line 6—6 of Fig. 1^b.

Figure 7 is a horizontal section taken along the line 7—7 of Fig. 1^b.

Figure 8 is a horizontal section taken along the line 8—8 of Fig. 3.

Figure 9 is a view in elevation partly in section of a circulating head.

Figure 10 is a vertical section of the circulating head showing the bushing to prevent circulation in a different position from that shown in Fig. 9.

Figure 11 is a fragmentary vertical section of a portion of the walking barrel and its operative relation with a plunger body.

Figure 12 is a view in perspective of the upper end of the plunger body.

Figure 13 is a view in elevation and partly in section of the valve control body.

Figure 14 is a view in perspective with parts broken away of a nut acting as a wrench to operate the valve controlling means.

Figure 15 is a horizontal section taken along the line 15—15 of Fig. 1^c.

Figure 16 is a fragmentary vertical section of the sand tester pump showing the control valves in closed position.

Figure 17 is a fragmentary vertical section of the operating means for the controlling valve stem.

Figure 18 is a fragmentary vertical section showing the valve controlling means in position for maintaining the back pressure valve in closed position.

Figure 19 is a horizontal section taken along the line 19—19 of Fig. 17.

Figure 20 is a view in elevation of a nut having external left hand threads and internal right hand threads.

Referring more particularly to the drawings 10 designates a collar which is screwed into a tubular piston rod 11 and is for the purpose of connecting the sand tester pump to a drill body, not shown. A ball race 12 embraces the piston rod 11 and in conjunction with the tubular bushing 13 which surrounds the piston rod, maintains the balls 14 in position. The packing ring 15 mounted in complementary annular grooves in the bushing 13 and the race 12 is of sufficient width to provide a lock for retaining the cap or race 12 on the bushing 13 and thereby prevents the cap from being forced away from the balls 14.

A packing 16 embraces the rod 11 and is located within an annular recess formed between an annular rib 17 formed interiorly of a tubular body member 18 which is threaded at its upper end at 19 on to the bushing 13 and at its lower end on a tubular back pressure valve body 20. The lower reduced end 21 of the bushing 13 engages the upper edge of the packing 16 and cooperates with the rib 17 and an inner wall of the tubular body 18 to form the annular pocket 30 for housing the packing. The valve body 20 provided with a plurality of inclined chambers 22 in each of which is slidably mounted a plunger valve 23 adapted to engage a seat 24 between a pair of communicating passages 25 and 26 formed in the valve body 20. A coil spring 27 is adapted to maintain the valve 23 on its seat 24. The valve body, has a depending reduced portion shown at 28 which is externally threaded at 29. The inner wall of the valve body is recessed as shown at 30, to provide an annular groove adjacent the inner end of the passages 25.

The tubular body 31 of the working valve 45 is screwed onto the threads 29 of the valve body 20 and depends from said valve body. Adjacent this point the hollow piston rod 11 terminates and is threaded at 32 into the upper end of a plunger body 33. This 50 plunger body has an enlarged chamber 34 at the upper end which receives a coil spring 35 having the upper end of the same in engagement with the lower end of the piston rod 11 while the lower end of said spring is 55 in engagement with the upper or outer end of a valve guide 36. This guide, it will be noted, is provided with ribs 37 arranged in parallel relation with the axis of a valve 38 and is adapted to engage a wall of the chamber 34. The lower end of the chamber is 60 provided with a valve seat 39 adapted to be engaged by the valve, as will be presently explained.

A stem 40 is secured to the valve 38 and 65 projects through a reduced passage 41 of

the lower reduced end 42 of the tubular plunger body. The reduced portion 42 of the plunger body provides for an annular groove 43 to receive a packing 44 which is in engagement at its upper end with a shoulder 45 of the plunger body and at its lower end with the upper end of a sleeve nut, which not only operates to hold the packing in place, but also provides a stop 46 for a wrench nut 47 which is screwed into the internal threads 48 of the lower reduced end 42 of the plunger body. The sleeve nut 46 engages the external threads on the lower end of said plunger body and is provided with a seat 49 adapted to receive the lower end of the nut 47. The valve control pin 50 is mounted in the central passage of a control member 51 forming the main body of the controlling device for regulating the opening and closing of the valve 38 against the tension of the spring 35.

The shearing pin 52 is inserted in a diametrically disposed passage in the pin 50 and has its ends projecting into sockets 53 in the spider 51. These sockets are provided at diametrically opposite points at the inner wall of the hollow member or sleeve 51. A U-shaped spring catch 54 is located within the hollow pin 50 and is adapted to support the shearing pin 52. The pin 50 is in the form of a spider mounted within the sleeve 51. The ends 55 of the spring catch 54 are located in passages 56 formed in the hollow sleeve or pin 50.

A valve control stem or member 60 is 100 square in cross sectional area and has its lower end reduced as shown at 62 and threaded at 63 to receive the internal threads 64 of a nut 65 having external threads meshing with the threads 66 formed on the inner 105 wall of a bushing 67 threaded at 68 into the upper end of the tubular body member 69 which is threaded at 70 to the lower end of the body member 31. The nut 65 has left hand threads 66 while the threads 64 110 are right hand.

The valve 71 is carried by the reduced portion 62^a and is adapted to engage a seat 72 carried by the body member 69. Resting on the valve is a sleeve 73 which is adapted 115 to retain a key 74 in position. A collar 75 is maintained within the upper end of the sleeve. Said pin has an end 73 by means of a pin 76 seated within a slot 77 in the sleeve projecting into a pocket 78 in the 120 collar. A spring 79 maintains the pin 76 in position. A collar 80 forms an extension of the upper end of the valve 71 and is received by the lower end of the sleeve 73. The ends of the pin 74 ride within the slots 125 81 in said sleeve. The stem 62^a terminates above the valve 71 and is received within a collar 75 mounted between the shoulder 83 of the tubular body member 69 and the upper end of a tubular member 84 which forms 130

the connection for the packer body 85. The guide 82 has a depending sleeve 86 through which the stem 62^a slides and a shearing pin 87 is carried by the lower end of the stem 5 and has its ends received in passages 88 in the sleeve 86. The lower end of the body 69 and the member 84 are threadedly connected together at 89 and the member 84 has a threaded passage 90 into which 10 is screwed the upper threaded portion 91 of the packer body or tapered mandrel 85. The mandrel is tapered, as shown at 92, and is received by a liner 93 mounted in the packing material 94 and also in the packer 15 washer 95 and extends downwardly to the lower packer washer 96. The liner is conically shaped and conforms to the shape of the mandrel 92. A reduced externally threaded pipe 97 is screwed into the lower 20 end of the mandrel 92 and the ring 96 and is embraced by a coil spring 98 having its upper end in engagement with the ring 96 and its lower end in contact with a retaining ring 99 carried by the unthreaded portion 25 100 of the pipe 97. The lower end 100 of the tubular member 97 acts only as a means for adjusting the tension of the spring on a mandrel, but provides a connection to receive a perforated pipe 101 which is threaded 30 at 102 into the lower end of the tubular member 100.

A circulating head shown in Figs. 9 and 10 consists of a main tubular body 105 which has threads 106 adapted to be screwed onto 35 the threads 107 of the connection 10, as shown in Fig. 1^a. The body member is provided with an annular groove 108 adapted to receive the inner end of a pin 109 which is pressed inwardly by a circular spring 110 40 mounted in a groove 111 of the tubular bushing 112 embracing the tubular body 105. This bushing prevents circulation of the fluid through passages 113 formed in the body member 105 until said bushing is 45 forced upwardly as shown in Fig. 10, whereby the passages 113 register with vertical slots 115 formed in the body member 116. Pins 114 are adapted to engage the lower 50 end of the bushing 112 for forcing the said bushing upwardly when the pins are elevated. These pins are moved upwardly until they strike the bearing cap 12 located at the upper end of the member 13. The pins 114 ride in vertical passages 115 formed 55 in the enlarged portion 116 of the body member. The lower end of the enlarged portion of the body member is counterbored at 117 which prevents the pins 114 from striking the walls of the well before the tool 60 has been set for operation.

Referring more particularly to Figs. 11 and 12, it will be seen that the working barrel 31 has pairs of radially disposed pins 120 adapted to be received within vertical 65 slots 121 in the upper end of the plunger

body 33. An offset slot 122 opens in the slots 121 and is adapted to receive the pin when the plunger body is rotated for locking the plunger body to the working barrel. Between each pair of slots 121 the 70 upper edge of the plunger body is provided with a cam surface 123 having inclined faces 124 and 125 directed downwardly from a central elevated point so that when the pins engage either inclined face it will 75 ride along said face and be projected into the slot 121.

The operation of my device is as follows:

In Figs. 1^a to 1^c, valves 38 and 71 are shown unseated and held in that position so 80 that the fluid from above may be pumped through the drill pipe and tester whereby all the cavings or any particles that may interfere with the positioning of the pump at the desired position, may be washed out 85 of the well. These valves are held in open position in the following manner:

Valve 38 is retained in open position by the valve controlled plunger 51 which in turn is held in elevated position by the valve 90 controlled nut 47, this nut being screwed to an upward position. The valve 71 is retained in an unseated position by the valve controlled stem 60 which is rotated and moved to an upward position by its connection with valve 71, and with key 74. 95

The packer 94 is seated in the seat which has been prepared above the formation to be tested. After said packer has been seated the plunger body 33 is lowered until the 100 valve controlled nut 47 engages the valve controlled stem 60. This stem is locked by a shear pin 87 and by turning the plunger body 33 to the right the valve controlled nut 47 having left hand threads travels to a 105 downward position, as shown in Fig. 2, and allows valve 38 to seat. The valve controlled nut 47 locks itself in position when the same engages bushing 46 and turns valve controlled stem 60. This rotation of the 110 stem shears off the pin 87, shown in Fig. 2. Since the stem 60 has a right hand thread as shown at 63, the stem will be screwed downwardly and cause valve 71 to seat. After this operation valves 38 and 71 are 115 seated and are free to the operation of the pump.

The pump is operated by raising and lowering the drill pipe which forces a test of the fluid from the formation and at this 120 time the packer 94 has cut off all outlaw fluids from above.

After the test has been made and it is desired to drain the pump and drill pipe when the pump is being pulled from the 125 well, the plunger body 33 is further rotated, as shown in Fig. 3, to the right whereby the valve controlled nut 47 is lowered over the valve controlled stem 60 and since the valve controlled stem nut 65 is threaded left 130

handed, this movement will raise the valve controlled stem 60 when it is turned to the right. Such an operation raises the valve 71 from its seat and at the same time the 5 upper end of the valve controlled stem 60 strikes the plunger pin 50 and shears pin 52 thereby forcing the valve controlled plunger pin 50 upwardly against the stem of valve 38. The spring catch 54 rests on 10 top of the valve controlled plunger 51 and holds both valves open so that the drill pipe and pump may be drained as they are pulled from the well. When the operator desires to remove the fluid from the well which 15 has been taken from the tested formation, the valves are left closed, as shown in Fig. 2. When the operator of the pump desires to maintain the circulation around the drill pipe to prevent said pipe and pump from be- 20 coming stuck in the well caused by cavings, the tubular body 10, in Fig. 1 is removed from the piston and the circulating head, as illustrated in Figs. 9 and 10 is substituted for the tubular body 10 and connected to 25 the piston rod by the threads 106 formed internally of the member 105. The plunger body 33 is then elevated to a point where the slots 121 are received by the pins 120. This prevents further relative movement of 30 the body at the time and also prevents the circulating head from being tripped so that circulation through the pump must be made directly through the central channel 130 of the circulating head. This condition of the 35 circulating head is maintained until the formation to be tested has been washed and the packer seats just above the formation which it is desired to test. The operator then turns plunger body 33 slightly to the 40 right and lowering it disengages the slots 120 from the pins 121. The tubular piston rod 11 and plunger body 33 are lowered into the tubular working barrel 31 until pins 114 strike the bearing cap 12 and force 45 the tubular bushing 112 upwardly to a point where the pin 109 engages itself in the slot 108 holding the bushing 112 in position to allow circulation of the fluid through the 50 passages 113. The pump valves are then op- 55 erated as previously desired for retaining said valves in an unseated position as shown in Fig. 1 and a test is taken from the sand at the time the circulation is maintained around the drill pipe to prevent the same 60 from being stuck in the well by the cavings. In order to determine whether the sand tester pump is pumping fluid, the pumps can be shut down for a short interval and the operation of the sand tester pump continued. If 65 the sand tester pump be forcing any fluid from the formation it will come through the circulating passages 113 and cause the fluid outside of the drill pipe to rise and overflow into the usual tanks (not disclosed) 65 which are mud kits, after it has been de-

termined that the sand tester pump is forcing the fluid from the sand which is being tested, circulation is again started around the drill pipe and such circulation brings out the fluid which has been taken from the sand. If this fluid is oil it will rise to the top of the circulating tanks and the quantity and quality of the fluid which said sand will produce can be determined by the amount of fluid which has been produced in a predetermined length of time.

The back pressure valves illustrated in Fig. 1^a include the elements 20, 27, 23, and the passages 26 provide an outlet for the fluid and air which may have escaped past the packing 16 and the packing 44 into the inner chamber of the working barrel 31 above the plunger body 33.

The packer indicated at 94 is so constructed that when an excessive pull is made to force the sand tester pump from the well, ring 95, packing material 94 and ring 96 will compress spring 98 and move down to the lower end of the tapered mandrel 92. This causes a space between the tapered mandrel and the packing material 94, thereby releasing the vacuum that has been placed on the formation and the packer by the operation of the sand tester pump. This allows the packing 94 to shrink whereby the same may be readily pulled from its seat.

If it is difficult to force the packer 94 from the seat the slots 120 in the plunger body 33 are re-engaged with the pins 121 so that a connection between the working barrel and the drill pipe is had. By this means the entire pump, as shown in Fig. 1, may be rotated during which time the packing material 94 may be torn from its seat. This operation just described, provides for an additional means for releasing the packer so that the pump may be readily removed from the well.

I claim:

1. A sand tester pump comprising a tubular body member, a plunger slidably mounted in the body member, a valve seat in the body member, a valve seat in the plunger, a valve in the tubular body adapted to engage the valve seat therein and a valve in the plunger adapted to engage the corresponding seat in said plunger, and means for causing successively seating and holding of said valves on their seats.

2. A sand tester pump comprising a tubular body member, a plunger slidably mounted in the body provided with a valve seat, a valve in the plunger adapted to engage said seat, a valve seat in the body, a valve in the body adapted to engage said seat, means for successively forcing the valves on the seats and for holding the valves to the said seats, and including means for independently operating the valves.

3. A sand tester pump comprising a tubu-

- lar body member, a plunger slidably mounted in the body provided with a valve seat, a valve in the plunger adapted to engage said seat, a valve seat in the body, a valve in the body adapted to engage said seat, means for successively forcing the valves away from the said seats, including means for independently operating the valves, a packer connected with the body member, and means for seating said packing member. 5
4. A sand tester pump comprising a tubular body, a plunger slidably mounted in the body and provided with a valve seat, a valve adapted to engage said seat, a valve seat in the tubular body and a valve adapted to engage said seat, a nut in the plunger adapted to be rotated for maintaining the first mentioned valve on the seat, a stem in engagement with the nut for causing the second mentioned valve to be removed and retained from its seat. 15
5. A sand tester pump comprising a tubular body member, a plunger slidably mounted in the body and provided with a valve seat, a valve adapted to engage said seat and a spring for maintaining said valve seated, a nut threaded into the plunger for forcing the valve from its seat, the tubular body being provided with a seat, a valve adapted to engage said seat provided with a stem having threaded connection and adapted to be rotated by the first mentioned nut for moving the second mentioned valve from the seat and retaining said valve in open position. 25
6. A sand tester pump comprising a tubular body, a plunger slidably mounted in the body and provided with a valve seat, a valve adapted to engage said seat, and having a depending stem, a nut threaded into the plunger adapted to be rotated for forcing the valve stem in one direction and for moving and retaining the valve away from its seat. 35
7. A sand tester pump comprising a tubular body a plunger slidably mounted in the body and provided with a valve seat, a valve adapted to engage said seat, and having a depending stem, a nut threaded into the plunger adapted to be rotated for forcing the valve stem in one direction and for moving and retaining the valve away from its seat, said tubular body having a valve seat, a valve adapted to engage said seat and provided with a stem, a hollow nut threaded into the body member and provided with internal threads, the last mentioned valve stem threaded in the second mentioned nut, and adapted to be rotated by the first mentioned nut for moving the second mentioned valve away from its seat, a plunger rod connected with the piston, the tubular body being provided with a plurality of passages connecting the exterior of the tubular body with the interior, a spring pressed valve controlling said passages. 45
8. A sand tester pump comprising a tubular body, a plunger slidably mounted in the body and provided with a valve seat, a valve adapted to engage said seat, and having a
- depending stem, a nut threaded into the plunger adapted to be rotated for forcing the valve stem in one direction and for moving and retaining the valve away from its seat, a packer mounted on the inner end of the tubular body, and means for forcing the packer in between the tubular body and the side walls of the well. 70
9. A sand tester pump comprising a tubular body, a plunger slidably mounted in the body and provided with a valve seat, a valve adapted to engage said seat, and having a depending stem, a nut threaded into the plunger adapted to be rotated for forcing the valve stem in one direction and for moving and retaining the valve away from its seat, a plunger rod connected with the piston, the tubular body being provided with a plurality of passages connecting the exterior of the tubular body with the interior, a spring pressed valve controlling said passages. 75
10. A sand tester pump comprising a tubular body a plunger slidably mounted in the body and provided with a valve seat, a valve adapted to engage said seat, and having a depending stem, a nut threaded into the plunger adapted to be rotated for forcing the valve stem in one direction and for moving and retaining the valve away from its seat, said tubular body having a valve seat, a valve adapted to engage said seat and provided with a stem, a hollow nut threaded into the body member and provided with internal threads, the last mentioned valve stem threaded in the second mentioned nut, and adapted to be rotated by the first mentioned nut for moving the second mentioned valve away from its seat, a plunger rod connected with the piston, the tubular body being provided with a plurality of passages connecting the exterior of the tubular body with the interior, a spring pressed valve controlling said passages. 90
11. A sand tester pump comprising a tubular body member, a plunger slidably mounted in the body member, a valve seat in the body member, a valve seat in the plunger, a valve in the tubular body adapted to engage the valve seat, therein and a valve in the plunger adapted to engage the corresponding seat in said plunger, means for simultaneously causing seating and holding of said valves on their seats, a plunger rod connected with a piston, the tubular body being provided with a plurality of passages connecting the exterior of the tubular body with the interior, and a spring pressed valve controlling said passages. 115
12. A sand tester pump comprising a tubular body member, a plunger slidably mounted in the body member, a valve seat in the body member, a valve seat in the plunger, a valve in the tubular body adapted to engage the valve seat therein and a valve

in the plunger adapted to engage the corresponding seat in said plunger, means for causing successive seating and holding of said valves on their seats, a plunger rod connected with the piston, a circulating head secured to the plunger rod and provided with a plurality of radial passages and means for closing said passages, and means for operating said closing means to release 10 said closing means from the passages.

13. A sand tester pump comprising a tubular body, a plunger slidably mounted in the body and provided with a valve seat, a valve adapted to engage said seat, and having a depending stem, a nut threaded into the plunger adapted to be rotated for forcing the valve stem in one direction and for moving and retaining the valve away from its seat, a hollow plunger rod connected with 20 the piston, a circulating head connected with the outer end of the plunger rod and provided with a plurality of radial passages, a sleeve for closing said passages, means carried by the head and adapted to be actuated 25 by the tubular body when the said plunger is

actuated for moving the said sleeve away from the radial passages.

14. A sand tester pump comprising a tubular body, a plunger slidably mounted in the body and provided with a valve seat, 30 a valve adapted to engage said seat, a valve seat in the tubular body and a valve adapted to engage said seat, a nut in the plunger adapted to be rotated for maintaining the first mentioned valve on the seat, a stem in 35 engagement with the nut for causing the second mentioned valve to be removed and retained from its seat, a hollow plunger rod connected with the plunger, a hollow circulating head secured to the plunger rod and having radial passages, means closing said radial passages, pins slidably mounted in the head and located between the sleeve and the outer end of the tubular body so that when the head is moved into engagement with the outer end of the tubular body, said pins will be reciprocated for moving the sleeve away 40 from the passages to permit circulation of fluid through said passages.

GEORGE F. LE BUS.
